METHOD AND APPARATUS FOR ASSEMBLING VENETIAN BLINDS

Harry Adelman, Pomona, Calif.

Application September 15, 1953, Serial No. 380,211

10 Claims. (Cl. 29—24.5)

This invention relates to a method and apparatus for assembling automatically Venetian blinds.

Various prior proposed means have been provided for facilitating the assembly of elongated Venetian blind slats in laterally spaced lifting tapes which are carried by a head member. Such prior proposed means have included partially automatic means, as for example, such means have been provided for feeding a Venetian blind cord through openings provided therefor in Venetian blind slats as the slats are assembled with respect to the lifting tapes. Other prior proposed means have included devices whereby the ladder openings are held expanded so that Venetian blind slats may be inserted thereinto and positioned in assembled relation with the lifting tapes. In such prior proposed means for facilitating assembly of Venetian blinds known to me, the Venetian blind slats have been fed into their respective slat receiving openings in the lifting tapes by hand.

This invention contemplates a method and apparatus for assembling Venetian blinds wherein the entire assembly operation is performed automatically and without individually handling the Venetian blind slats.

An object of this invention is to disclose and provide a method and apparatus for automatically assembling Venetian blinds wherein the operation is automatic commencing from the withdrawing of ribbon stock material from which the slats are formed from a reel to the complete assembly of a pre-selected number of slats with the lifting tapes and lifting cords.

Another object of this invention is to disclose such an automatic apparatus for assembling Venetian blinds which is simple in construction, which saves considerable labor, and which accomplishes the assembly operation in an expeditious manner.

A further object of this invention is to disclose and provide a method and apparatus for assembling Venetian blinds wherein the slats are successively fed into respective aligned openings of lifting tapes and then raised step-by-step so as to permit succeeding slats to enter into their respective openings in said lifting tapes.

A still further object of this invention is to assemble Venetian blind slats as above-mentioned wherein the Venetian blind lifting cord is threaded into openings provided therefor in said slats as said slats are raised in step-by-step fashion.

A further object of this invention is to provide specific means for expanding slat receiving openings provided in said lifting tapes just prior to the passage therethrough of an advancing slat.

This invention contemplates a method and apparatus for automatically assembling Venetian blinds wherein an advancing slat actuates means for advancing a succeeding slat along a pre-selected path of travel and also actuates means for lifting a slat positioned in assembled relation with lifting tapes out of said normal path of travel.

A still further object of this invention is to disclose and provide an apparatus for assembling Venetian blind slats or elongated strip elements in parallel lines whereby rapid

2

production of assembled units in commercial quantities is achieved.

Generally speaking, the method and apparatus of this invention contemplates unwinding strip material from a reel, punching selected spaced lifting cord openings therein and cutting to a pre-selected slat length, successively advancing said pre-cut punched slats in a line along a horizontal path into an assembly zone wherein Venetian blind lifting tapes are positioned in selected spaced relation with slat receiving openings in alignment, guiding a slat along said path through said slat receiving openings, and then stopping said advancing slat at a preselected position whereby the lifting cord openings are properly aligned with said lifting tapes for receiving a lifting cord. The advancing slat actuates means for advancing a second slat along said path of travel. Before the second slat reaches the assembly zone, the first slat actuates means for raising the first slat vertically a selected distance so as to position a lower set of slat receiving openings in said horizontal path for reception of the second slat. As succeeding slats are assembled with the lifting tapes and raised in a vertical planar zone in step-by-step fashion a lifting cord is threaded through each of the lifting cord openings in the assembled slats. This sequence of steps is repeated until a preselected number of slats have been assembled in the lifting tapes at which time operation of the apparatus ceases so that the assembled slats and lifting tapes may be removed therefrom.

Other objects and advantages will be readily apparent from the following description of the drawings in which an exemplary of the embodiment of this invention is shown.

In the drawings:

Fig. 1 is a fragmentary diagrammatic view of an apparatus embodying this invention.

Fig. 2 is an enlarged side view of the slat assembly zone and structure therefor shown at the right of Fig. 1.

Fig. 3 is an end view of Fig. 2 taken from the right.

Fig. 4 is a fragmentary enlarged side view of a device for expanding a slat receiving opening.

Fig. 5 is a perspective view of Fig. 4 with the lifting tape eliminated therefrom.

Fig. 6 is a top view of Fig. 4.

Fig. 7 is a fragmentary view showing the device of Fig. 4 expanded within a slat receiving opening.

Fig. 8 is a diagrammatic perspective view of a lever and linkage arrangement automatically lifting one end of an assembled slat.

Fig. 9 is a diagrammatic perspective view of drive means for the slat assembly apparatus shown in Fig. 1.

Fig. 10 is a fragmentary perspective view of guide means for the movable support means carried by the frame.

Fig. 11 is a fragmentary perspective view of means for threading a lifting cord through said slats as they are raised step-by-step.

Fig. 12 is an enlarged view of the end of the threading needle shown in Fig. 11.

Fig. 13 is a fragmentary perspective view of guide means and a first switch means carried by the frame in the horizontal path of travel of a slat.

Fig. 14 is an end view of Fig. 13 taken from the right thereof.

Fig. 15 is a fragmentary perspective view of a second and final switch means positioned in said horizontal path of travel of a slat for stopping advancement of said slat.

Fig. 16 is a fragmentary diagrammatic view of a modification of the means for intermittently raising the slat assembly.

The apparatus of this invention is generally shown in Fig. 1. A supply roll 20 carries and provides a quan-

ity of continuous metal strip material from which metal Venetian blind slats may be made. The free end of the strip material may be fed between pull roll means generally indicated at 21 for withdrawing strip material from the supply roll. The pull roll means 21 advance the strip material into a stamping and cutting machine generally indicated at 22, wherein the strip material is cut to selected slat length and is also punched with selected longitudinally spaced lifting cord openings. The precut punched slat is then advanced by the cutting machine to a friction drive means generally indicated at 23 for advancing a precut slat at a greater rate of speed than the advancement of said slat through the cutting machine.

The friction drive means 23 advances a slat in a horizontal path into a vertical assembly zone defined by an apparatus, generally indicated at 24 for automatically assembling a plurality of slats. The apparatus 24 receives each slat along a horizontal path for assembly with spaced lifting tape means having horizontally aligned slat receiving openings. When a slat is in position in one set of openings, the lifting tape means and slat are lifted upwardly a preselected distance so that a following slat may be received in a lower set of openings and in assembly with the lifting tape means. Slats are intermittently fed to the friction drive means 23 in correlated timed relation with the assembly of the slats in apparatus 24 by means actuated by the position of a slat being assembled. In this manner a preselected number of slats are automatically assembled in lifting tape means.

To facilitate explanation of the apparatus of this invention, it is understood that a Venetian blind comprises a header member 26, a bottom member 27, and a plurality of horizontally spaced lifting tape means 28 connected to and extending between the header and bottom members 26 and 27. Each lifting tape means includes a plurality of slat receiving openings 29 (Figs. 4 and 11) defined by ladders 30 alternately laterally offset with respect to the longitudinal axis of the tape means. Lateral spacing between adjacent offset ladders 30 is sufficient to accommodate therebetween a lifting cord 31 which extends through lifting cord openings 32 provided in each slat 33 in alignment with the axis of lifting tapes 28. This arrangement of a Venetian blind assembly is well known.

In detail, the supply roll 20 may be suitably positioned upon an axle 35 for facilitating turning of the roll. The axle 35 may be mounted upon standards 36 in well-known manner. The strip material of supply roll 20 may be of any selected metal material having painted or enameled surfaces and having a slightly convex-concave cross section to lend strength to the strip against bending.

The pull roll means 21 comprises two sets of longitudinally spaced rollers, each set comprising top and bottom rollers 38 adapted to frictionally receive therebetween strip material from the supply roll for pulling the strip material from said roll. The rollers 38 of each set may be driven by any suitable means and in this example are driven in timed relation to the cutting machine 22 as later described. A slack takeup idle roll (not shown) may be employed with the pull roll means 21.

The stamping and cutting machine 22 is of well-known make and manufacture and is designed to receive in a horizontal plane strip material advanced thereto by pull roll means 21. The cutting machine includes dies whereby the strip material may be cut to a preselected length and whereby lifting cord openings 32 may be stamped or punched thereinto in proper preselected spaced relation. The cutting machine 22 may include an auxiliary stamping machine 39 operated in correlation with machine 22 for punching intermediate lifting cord openings in a slat supported by more than two lifting tapes. The cutting machine also includes a counting device 40

5 by which the number of slats cut by the machine are automatically counted. The counting device is connected to the machine in well-known manner so that when a selected number of slats have been cut by the machine, the machine will automatically stop.

A section of strip material, which has been punched and cut by machine 22 and which may then be identified as a slat 33, is advanced by the cutting machine along a straight, horizontal path to friction drive means 23. The friction drive means 23 includes a bottom drive roller 41 and a top idle roller 42 of smaller diameter carried by an arm 43 pivotally connected, as at 44, to an extension of the cutting machine 22. The roller 42 is biased downwardly into contact with a slat 33 passing thereunder by spring means 45. The bottom roller 41 is driven at a rate of speed greater than the pull roll means 21 so that a slat 33 may be advanced more rapidly thereby into the assembly apparatus for positively spacing a slat 33 forwardly of the succeeding or following slat.

20 The assembly apparatus 24 (Figs. 2 and 3) comprises an upstanding frame structure including longitudinally spaced parallel vertical rails 47 made of any suitable metal section, such as a channel section shown. The rails 47 25 may be connected to a base member 48 which may be supported on any suitable foundation. The spaced rails 47 may be interbraced for rigidity in any suitable manner (not shown) and may include diagonally downwardly directed frame members 49.

25 Vertically movable carrier means 50 are carried by the frame structure and are guided by the vertical rails 47 for vertical reciprocal movement. The carrier means 50 may include a longitudinally extending horizontal angle iron member 51 of a length sufficient to accommodate the greatest width of a Venetian blind to be assembled. The member 51 is supported forwardly of the rails 47 by spaced rearwardly extending horizontal beams 52 secured to the member 51 as by welding. Each member 52 may be secured as by welding to a vertically disposed plate 53 lying in a plane perpendicular to and adjacent to the plane of a rail 47. Each plate 53 carries a pair of vertically spaced guide rollers 54 (Figs. 2 and 10) adapted to contact the front surface of rail 47. Each plate 43 also carries an inner guide roller 55 lying between rollers 54 and adapted to bear against the inner surface of the front flange of the channel rail 47. The plate 53 may also carry a side-40 wardly extending arm 56 upon which may be mounted a guide roller 57 adapted to rollingly contact the outer surface of the web of rail 47. It will thus be readily apparent that the member 51 is positively and accurately guided by rails 47 through the plurality of guide rollers 54, 55, and 57.

45 Means for raising and lowering the carrier means 50 may include a pair of longitudinally spaced endless chain means 59 arranged adjacent to said rails 47 and spaced from the outboard sides thereof. The outboard ends of arms 56 carried by plates 53 may be attached to a section of the chain means 59 as by nut and bolt assemblies 60 extending through the end of an arm 56 and the openings between rollers of the chain. Each chain means 59 is carried by a pair of vertically spaced sprockets 62, the top sprocket 62 being rotatably mounted about a longitudinally extending shaft 63 journally carried by the frame structure at the top thereof. Each lower sprocket 62 is mounted on an end of a rotatably driven shaft 64 which extends longitudinally of the frame structure and parallel to shaft 63. Each chain means 59 may carry on the rearward lay thereof a suitably selected counterweight means 65 for counterbalancing the weight of the movable carrier means 50 and the weight of the header member 26 and lifting tapes associated therewith.

50 Means for driving sprockets 62 in an intermittent fashion in order to raise the carrier means 50 in step-by-step fashion may comprise a motor 67, preferably reversible, or electrically connected so as to raise and lower

the carrier means. The motor 67 (Fig. 9) drives a belt pulley means generally indicated at 68 of well-known form, the driven end of said pulley means being connected to a solenoid actuated single revolution clutch means 69. The clutch means 69 is connected to a forwardly directed shaft 70 provided with a worm gear 71 which engages with a gear 72 carried by the bottom sprocket shaft 64. Thus upon actuation of the single revolution clutch means 69 the chain means 59 will be moved vertically for a preselected distance as determined by the ratio of gears 71 and 72 during one revolution of the clutch 69.

Means for supporting the head member 26 of a Venetian blind from the movable carrier means 50 may comprise a plurality of longitudinally spaced hanger members 74. Each hanger member 74 includes a top rearwardly bent over end portion 75 which forms, with the main portion of member 74, a recess 76 adapted to slidably engage an upstanding flange 77 of the support member 51. The lower end portion 78 of member 74 is bent outwardly so as to lie in a horizontal plane. The header member 26 is seated on said horizontal end portion 78 and is thus supported horizontally in a vertical planar assembly zone forwardly of rails 47 of the frame structure.

Means for guiding a slat 33 in a horizontal path across the vertical zone defined by members 74 is provided by a longitudinally extending horizontal member 80 which is carried by spaced forwardly extending brackets 81 attached to rails 47 in suitable manner. Each bracket 81 may be offset upwardly as at 82 in order to provide vertical clearance for adjustably sliding various guide devices and actuating means along the member 80 to adjust the apparatus to various widths of Venetian blinds to be assembled. The member 80 may be fabricated from a pair of angle irons having their horizontal flanges 83 secured together in any suitable manner and presenting their vertical flanges 84 in the same vertical plane. The member 80 may be of substantially the same length as the movable carrier member 51 so as to conveniently carry guide means for a slat of any selected length.

The member 80 lies in the same horizontal plane as the horizontal path of movement of a slat 33 as it departs from the friction drive means 23. Means are provided for supporting and guiding each slat 33 as it advances in said horizontal path, said guiding means also serving to expand and hold open slat receiving openings 29 in the lifting tape means 28. Such support, guide, and slat opening means are generally indicated at 86 and may be associated with each lifting tape means 28 except the most remote tape means as shown on the drawings.

The guide means 86 are shown in detail in Figs. 4, 5, 6 and 7. As best seen in Fig. 5, each guide means 86 includes a clip member 89 having a top bent over portion 90 adapted to receive and adjustably slidably engage vertical flange 84 of the member 80. The member 89 includes a pair of parallel spaced forwardly extending arms 91 which are adapted to receive therebetween a lifting tape means 28, as seen in Figs. 4 and 6. The arms 91 serve to guide and hold the lifting tape means 28 in vertical parallel relation in the assembly zone while the movable carrier means 50 is intermittently raised.

The proximate arm 91 with respect to the direction of advancement of a slot 33 may carry a longitudinally extending bracket 92 having a depending flange 93 secured thereto as by welding. A horizontally extending portion 94 supports a longitudinal slidable element 95 which carries a pair of longitudinally spaced depending pins 96 and 97. The pins 96 and 97 extend through respective elongated slots 98 and 99 in portion 94 for slidable movement therein. The element 95 may be provided with a pointed end 100 having a seating flange 102 defined by diagonally extending shoulders or edge faces 101 and which is adapted to carry a pair of angle sections V or diagonally arranged wedge elements 103.

Each element 103 includes a seating portion 104 carried by flange 102 and an upstanding inwardly tilted flange

105. The inward tilt of flange 105 serves to retain a slat against upward displacement during advancement. The leading edge of each flange 105 is inclined rearwardly to facilitate entry beneath a ladder lying in the path of a slat. Each element 103 is pivotally mounted on the extended seating flange 102 adjacent its outer and rearmost corner by a pin 106 fixed to the element 103. Each pin 106 may be bent into the form of a crank and normally extends laterally outwardly from element 95. The remote end of each pin 106 is connected to one end of a spring 107 which is secured at its other end as at 108 to the depending flange 93. The springs 107 bias the elements 103 into closed pointed or wedge relationship, as shown in Fig. 5.

15 In operation of the guide means 86, as a slat 33 is advanced along said horizontal path (with slat receiving openings 29 aligned therewith) the leading end of said slat passes over the element 95 and into the V formed by upstanding flanges 105 of elements 103. The advancing 20 slat 33 causes element 95 and elements 103 to advance longitudinally therewith until the crank shaped pins 106 contact as at 110, Fig. 7, surfaces of the adjacent arm 91. Contact with the arm 91 causes the crank shaped pins 106 to pivot rearwardly and thus cause the elements 103

25 which were disposed in closed V-shape arrangement to open and move sidewardly into parallel relation against the vertical ribbons 28a of lifting tapes 28 so as to positively hold the slat receiving opening 29 in expanded position. A slat 33 is thus guided through a slat receiving 30 opening 29 without interference by the tape means and advances toward the next lifting tape means and its associated guide means 86.

The guide means 86 is automatically retractable into its normal position when the leading edge of a slat 33 35 clears the flanges 105, said flanges being retracted in parallel relation and serving as guides for the rest of the slat. Upon clearance of a slat 33, a spring 111 which is connected at one end to a depending stud 112 carried by the horizontal portion 94 and at its other end to a downwardly extended portion of pin 97 which is carried by the movable element 95, serves to bias the movable element 95 opposite to the direction of slat advancement until the pins 96 and 97 contact the rear walls of the slots 98 and 99. The springs 107 cause elements 103 to 40 close into normal V arrangement when a slat 33 is lifted vertically upon completion of its advancement into the lifting tapes.

45 As a slat 33 approaches the remote lifting tape means 28 a switch means generally indicated at 115 is 50 interposed in its path for the purpose of electrically actuating the cutting machine so as to punch and cut a succeeding slat and to advance a succeeding slat along said horizontal path. The switch means 115 is adapted to be slidably adjusted along the horizontal member 80 and is best seen in Figs. 13 and 14.

55 In front of switch means 115 may be provided a platform 116 carried by member 80 and having a top flat surface lying just below path of travel of the slat 33. The bracket 116 includes a pair of longitudinally spaced depending legs 117, the forwardly facing leg 117 carrying a longitudinally extended angle bracket 118. The angle bracket 118 includes a horizontal portion 119 having a top surface in the plane of the top surface of plate 116. 60 The forward edge of portion 119 may be curved slightly downwardly to form an apron 120 so as to receive and guide upwardly if necessary the leading edge of a slat 33. Side margins of horizontal portion 119 may carry downwardly biased overlying hinge leaves 121. The hinge leaves 121 are provided with upwardly curved slat facing 65 end portions 122 so as to cooperate with the apron 120 to form a mouth into which the leading edge of slat 33 may be positively guided. A slat 33 entering the mouth is held down against the top surfaces of the portion 119 and the plate 116 by the biased leaves 121 so as to posi-

tively contact and strike an upstanding switch contact element 123 positioned adjacent the distal leg 117 of the bracket 116.

The switch contact element 123 which projects upwardly into the path of a slat 33 is pivotally mounted intermediate its ends, as at 124, Fig. 2, in a recess formed in a supporting member or arm 130. The lower end of contact element 123 abuts against a circuit-making element 126 carried by a limit switch 127. Thus as the leading edge of slat 33 hits contact element 123, the contact element pivots about its pivot point 124 and causes the circuit-making element 126 to close an electrical circuit. The contact element 123 is biased forwardly by a spring 123a compressed between element 123 and a vertical lug 125 carried by arm 130.

Upon closure of the circuit by member 126, the switch means 127 causes actuation of the cutting machine to punch and cut a succeeding slat. It also causes a longitudinally extending rotatably mounted member 129 to rotate in a clockwise direction for positively drawing the contact element 123 downwardly and out of the path of the slat element.

The contact element 123 is carried at the extremity of an arm 130 which is pivotally mounted inwardly of the assembly zone for rotation about a pivotal axis at 131. A depending arm 132 is integral with arm 130 and extends downwardly into engagement as at 133 with the rotatable member 129. Thus as the member 129 is rotated clockwise, the depending arm 132 and likewise the horizontally extended arm 130 are rotated counterclockwise whereby contact element 123 is withdrawn below the path of a slat 33.

The electrical circuit means for actuating the cutting machine is not shown because it is well known and any suitable circuitry may be employed.

The means for rotating the member 129 is diagrammatically illustrated in Fig. 8, and may include a pivoted crank member 135 extending outwardly from the cutting machine and pivotally connected at 136 to one end of a lever 137. The lever 137 may be pivoted intermediate its ends at 138 and is pivotally connected at its opposite end as at 139 to a link 140 which is pivotally connected at its lower end at 141 to an arm 142 fixed to a shaft 143. The shaft 143 is journaled mounted adjacent friction drive means 23 and carries a crank arm 144 at its other end. The crank arm 144 is connected to a link 145 which is secured to a rod 146 which is accommodated between the angle flanges of the member 129 and secured thereto as by welding. The rod 146 extends for substantially the entire length of member 129 to lend stiffness thereto. Upon actuation of the cutting machine, the crank arm 135 is rotated and this rotational movement is transmitted through the lever and linkage means shown in Fig. 8 to the member 129 for rotating said member clockwise through a selected angle whereby the contact element 123 will be positively lowered by movement of the angularly disposed arms 130 and 132. In the brief moment that the slat 33 is stopped by contact element 123, the friction drive means 23 slips on the surfaces of the slat engaged by rolls 41 and 42. The engagement is not sufficient to cause buckling of the slat.

After a slat 33 has passed over the switch means 115, it is finally positioned by a second switch means 150 positioned at the end of member 80 so that lifting cord openings 32 in each slat will be properly aligned between the ladders 30 of each of the lifting tape means 28. The leading edge of a slat 33 is guided into abutment with the final positioning switch means 150 by means of an upwardly inclined trough 151 hung on upstanding flange 84 of the member 80 by a bent-over strap-like portion 152. The trough member 151 includes a bottom wall 153 and upstanding side walls 154 which receive therebetween the leading end of a slat 33. The leading edge of a slat 33 strikes a switch element 155 which is caused

to be moved in the direction of advancement of the slat for closing an electrical circuit.

Closure of this circuit causes actuation of the solenoid operated single revolution clutch 69 whereby shaft 70 is rotated for one revolution and the chain means 59 are thereby moved a preselected distance to cause the carrier means 50 to be lifted. Lifting of carrier means 50 raises the slat 33 which is now supported by the ladders 30 of the tape means 28 and raises the assembled slat out of said horizontal path of travel. The height through which the slat is lifted is virtually the distance between ladders 30 so that the immediate adjacent lower set of aligned slat receiving openings 29 are positioned in said path of travel for reception of a succeeding slat 33.

To prevent multiple actuation of the switch means 150 by a slat 33 and which might cause the single revolution clutch to operate twice or more, positive means are provided for lifting the leading end of a slat 33 upwardly and out of contact-making position with the switch member 155. Such means are shown in Fig. 15 and in Fig. 3. Shaft 70 carries outwardly of the worm gear 71 and extension 157 which carries at its outer end a disk 158 having mounted thereon an eccentric pin 159. The eccentric pin 159 is connected to one end of a lever 160 which is adjustably connected at its other end as at 160a to an arm 161 which is secured to the member 129 as at 162. Upon rotation of the shaft 70 the arm 161, through the lever and eccentric connection described, causes member 129 to rotate clockwise and to lift upwardly a slat lifting pin 164.

Slat lifting pin 164 may be pivotally connected as at 165 to a bracket 167 carried by the member 129. The upper portion of pin 164 is guided through a ported lug 168 to an aligned opening 169 in the bottom wall 153 of the trough 151. Upon lifting of pin 164 by rotation of member 129, the top edge of pin 164 contacts the lower surface of the leading end of a slat 33 and lifts the slat upwardly and beyond the top edge of contact member 155. Before the pin is dropped from this position, the lifting tapes 28 will have engaged a slat 33 so as to maintain it in a position above the switch member 155.

Means for automatically threading a lifting cord 31 through aligned lifting cord openings 32 as slat 33 is raised in assembly with the lifting tape means is illustrated in Fig. 11, Figs. 2 and 3. In Fig. 3 it will be noted that the frame structure includes horizontal outwardly extending top members 172 secured to the rails 47. The members 172 may be diagonally braced by members 173. Their forward end portions lie in the vertical assembly zone defined by header member 26 and the depending lifting tape means 28. The forwardly extending members 172 may be connected by a horizontal transversely extending bar 173. The bar 173 serves to support a plurality of rigid elongated threading needles 174 which extend downwardly through guiding ports provided in guide brackets 178 carried by the carrier means 50 and through the lifting cord openings 179 in the header member 26. The lower end of each threading needle 174 is positioned just above the horizontal path of travel of a slat 33 as seen at 180 in Fig. 3. Lifting cords are threaded in an eye 181 provided in the lower end of the needle 174 said lifting cords passing through the opening 179 in the header member 26. The remaining portion of the cord may loosely lie adjacent to the header member so that it may automatically be fed therethrough as the header member is raised during operation.

In operation of the apparatus of this invention described above, it is understood that a header member 26 with a selected number of lifting tape means 28 may be assembled in usual fashion by securing upper end portions of said tapes to the header members at preselected spaced intervals. The lower ends of said tapes may be connected in usual manner to bottom rail 27. After the header member 26 and rail 27 and lifting tapes 28 have been connected together, the header member may

be placed on the carrier means 50 by simply slidably adjusting the members 74 so that they lie between lifting tape means and laying the header member on the horizontal supports 78. Initially the header member lies just above the horizontal path of travel defined by the member 80 and the guide means carried thereby. The lower portions of the tape means 28 may loosely lie on the floor.

When the apparatus is started by well-known electrical means, the pull roll means 21 pull a portion of the strip material from supply roll 20 and feed the free portion into the stamping and cutting machine. The stamping and cutting machine is adjusted to cut the strip material to a preselected length and also to punch lifting cord openings therein at the preselected spaced intervals. The strip material thus fed into the cutting machine is cut and punched and is ejected therefrom by the roll means 21 until the cut slat is received by the friction drive means 23. The friction drive means 23 accelerates the rate of advancement of a slat 33 along the horizontal path of travel of the assembly apparatus 24. A guide means 86 is positioned closely adjacent to the friction drive means so as to initially receive the leading end of a slat 33 and to guide the slat through the first of the set of slat receiving openings 29 immediately adjacent the header member 26. The friction drive means advances the slat along said path through the several aligned slat receiving openings 29 until the leading edge of the slat contacts switch means 115.

The switch means 115 then causes actuation of the cutting machine and pull roll means 21 for pulling and feeding additional strip material from the supply roll and cutting a second slat 33. At the same time the switch means 115 causes rotation of bar 129 so as to positively lower the contact element 123 out of the path of the advancing slat. As the slat advances to switch means 150, it is guided through the remaining slat receiving openings in the remote lifting tape means 28 and upon contact with member 155 it is accurately ultimately positioned in assembled relation with the lifting tape means and with openings 29 in alignment with the threading needles 174. Actuation of the switch means 150 by slat 33 causes the sprocket and chain means 59 to turn through a preselected distance whereby the assembled slat is lifted out of and above the horizontal path so as to position the immediately adjacent lower set of slat receiving openings in said horizontal path for reception of a succeeding slat 33.

This operation is repeated until a desired number of slats has been assembled in the lifting tape means. The machine is automatically stopped by the automatic counting device 40 when the selected number of slats has been assembled. In final assembly position the carrier means 50 is located adjacent the top of the rails 47 and the Venetian blind thus assembled hangs downwardly therefrom. The carrier means 50 may then be lowered so as to close the Venetian blind and form a compact bundle of assembled Venetian blind slats. The header member 26 with the assembled slats and tapes may be suitably secured in such position by any convenient means as by securing ropes or tapes and may then be lifted as a bundle from the machine.

Lowering of the assembled Venetian blind slats may be automatically stopped by means of a switch means carried by one of the rails 47 and having a depressible switch contact element 186. The switch means 185 is electrically connected to the drive means for stopping the drive means in well-known manner. The carrier means 50 may include a pivotally mounted switch arm 187 carried by plate 53 and biased downwardly by a spring 188. When the carrier 50 is lowered, the end of arm 187 contacts the depressible switch element 186 for actuation thereof. It is understood other suitable means may be employed to control and stop the downward movement of the assembled Venetian blinds.

It may be noted that two different embodiments of switch means actuated by an advancing slat have been illustrated, one being switch means 115 for causing actuation of certain portions of the apparatus, and the other 5 being switch means 150 for finally positioning and causing lifting of the carrier means 50. It is understood that switch means 115 may be employed in place of switch means 150 for performing the same operative functions as described for switch means 150. When a switch means 115 is so employed, a suitable rigid stop member may be provided for ultimate longitudinal positioning of a slat so that the cord receiving openings in the slats will be properly aligned.

In Fig. 16 is illustrated a modification of the means 15 for intermittently raising the carrier means and assembled Venetian blind slats in step-by-step fashion. The modification illustrates a simply operative means whereby assembly of Venetian blind slats having ladder openings including other than standard may be readily accomplished by the machine. When the slot receiving openings 20 are of different height and the slats received therein are of greater width than standard, it will be readily apparent that the lifting tapes must be raised a distance greater than the distance required for a standard tape and slat 25 assembly as described hereinabove.

In this modification motor 67 is connected to drive shaft 70 through a well known type of friction clutch means 189 instead of the single revolution clutch hereinabove described. The friction clutch means 189 may be solenoid actuated into engaging and disengaging position so that while the motor is running continuously the drive of shaft 70 may be electrically intermittently interrupted.

The solenoid actuated clutch means 189 may be connected to a switch means 190 carried on the distal leg 91 of the first guide means 86. The switch means 190 includes an upwardly biased reciprocally movable contact pin 191 which is adapted to contact as at 192 a lower end 193 of a pivoted slat engaging arm 194. The other end of arm 194 extends into the vertical assembly zone and into a position above the horizontal path of travel of a slat 33. When a slat 33 assembled with the lifting tapes is raised upwardly by actuation of the drive means by the switch means 150, the assembled slat 33 contacts 35 and lifts the arm 194 so as to depress the push pin 191. Depression of the pin 191 closes an electrical circuit which causes the solenoid actuated clutch 189 to be disengaged so that drive shaft 70 is disconnected from the drive means. Vertical movement of the assembled slat 40 is thus stopped at a point where the set of slat receiving openings therebelow are substantially aligned and open for the reception of a succeeding slat 33. When the succeeding slat strikes switch means 150 the clutch means 189 is actuated to engaged position for raising the slat 45 and assembly. Arm 194 is again in position to be contacted by the second slat for disengaging the clutch means and again stopping the vertical movement of the assembled slats. This operation is repeated until the assembly is 50 completed.

It will thus be apparent that the modified means for intermittently raising assembled slats automatically adjusts the height of the slat lifting step to any spacing of the ladders in the lifting tape means.

It should also be noted that after the apparatus of 55 this invention has begun to operate, virtually all succeeding operations performed by the machine are actuated and controlled by an advancing slat. The slat is positively and accurately guided in a horizontal path of travel. The slat also actuates means for opening and maintaining in open position the slat receiving openings.

It is understood various modifications and changes 60 may be made in the apparatus of the invention described above and all such changes which come within the scope 75 of the appended claims are embraced thereby.

I claim:

1. In an apparatus for automatically assembling Venetian blind slats in spaced lifting tapes presenting sets of aligned openings for receiving said slats the combination of: a frame structure; movable carrier means mounted on the frame structure adapted to support said lifting tapes in normal parallel spaced relationship with sets of openings in alignment and for movement in a vertical planar zone; means for advancing a Venetian blind slat into said zone along a horizontal path extending through a set of aligned openings; means carried by the frame structure extending into the planar zone for supporting and guiding an advancing slat along said path into assembled relation with said lifting tapes; means actuated by said advancing slat for causing the movable carrier means to move the assembled slat out of said horizontal path upwardly in said planar zone a pre-selected distance and for moving a lower set of aligned openings into said path for receiving a succeeding slat in assembly with the spaced lifting tapes; said actuated means including a rotatable member extending parallel to said horizontal path, and means including an upstanding pin vertically movable by the rotatable member to positively lift said slat out of said horizontal path.

2. In an apparatus for assembling Venetian blinds provided with a header member carrying depending spaced lifting tape means presenting horizontally aligned sets of slat receiving openings the combination of: an upstanding frame structure including spaced vertical frame members; vertically movable carrier means carried by and guided by said frame members; means on said carrier means adapted to support a header member and depending spaced lifting tape means connected thereto for movement in a vertical zone; guide means carried by the frame structure in said vertical zone and defining a horizontal path for a slat to be advanced across said vertical zone through a set of aligned slat receiving openings; means for advancing a slat along said horizontal path; means on the frame structure for longitudinally positioning a slat received in said slat receiving openings; means actuated by said slat when positioned for intermittently raising said movable means a pre-selected distance to position an adjacent lower set of slat receiving openings in said horizontal path to receive a succeeding slat; said actuated means including a member extending alongside said horizontal path and rotatable about its longitudinal axis, and means operable by rotation of said rotatable member to engage and lift one end of said slat out of said path.

3. In an apparatus for automatically assembling slats in spaced holding means presenting sets of aligned openings for receiving said slats, the combination of: a frame structure; movable carrier means carried by the frame structure adapted to support said spaced holding means in normal parallel spaced relationship with sets of openings in alignment for movement in a planar zone; means for advancing a pre-cut slat into said zone along a path extending through a set of aligned openings; means carried by the frame structure extending into the planar zone for supporting and guiding an advancing slat along said path into assembled relation with said spaced holding means; means actuated by said advancing slat for causing the moveable carrier means to move the assembled slat and holding means out of said path and at an angle thereto for a pre-selected distance for moving a lower set of aligned openings into said path for receiving a succeeding slat in assembly with the spaced holding means; said actuated means including a longitudinally extending rotatable member, and a switch element extending into said path to be contacted by a slat, said rotatable member being operably connected to the switch element to retract said switch element out of said path.

4. An apparatus as stated in claim 3 wherein means for guiding a slat include spring-biased, oppositely disposed elements positionable in said slat receiving open-

ings for positively holding the slat receiving openings open.

5. In an apparatus for assembling strip elements in parallel lines in a non-rigid strip holding means adapted to separately retain each element in assembly therewith, the combination thereof: a frame structure; intermittently upwardly movable means carried by the frame structure adapted to support strip holding means for movement in a vertical planar zone; means carried by the frame extending into the planar zone in the same direction as the parallel lines to be arranged by the strip elements for supporting and guiding in a horizontal plane an advancing strip element along a selected path into assembled relation with the holding means; switch means carried by the frame including a switch element extending into said path for causing the movable means to move the assembled strip element out of said path for receiving a succeeding element; rotatable means carried by said frame and extending parallel to said path; and means for rotating said rotatable means upon contact of a slat with said switch element to retract said switch element out of said path.

6. An apparatus as stated in claim 5 wherein means are carried by the frame and longitudinally movable relative to the frame by an advancing slat for entering an aligned opening to maintain said opening in expanded relation for receiving and passing therethrough the advancing portion of a slat.

7. A support and guide means for guiding an elongated strip element along a path and for maintaining expanded an opening defined by compliant material while the strip element is advanced therewith, comprising in combination: a stationary means supported adjacent said path; a member carried by the stationary means and slidably movable relative thereto along and in the direction of said path, said movable member being provided with a pair of pivotally mounted flanged elements normally biased into V arrangement and extending into the path of an advancing strip element to receive the leading end of the strip element within the V in contact therewith, whereby the pair of flanged elements are advanced as a wedge into said opening; means carried by the stationary means and crank means carried by the pair of elements cooperable to urge said pair of elements into parallel relation within said opening to hold the compliant material out of the path of a strip element advanced through said opening along said path; and means for retracting said movable element and said pair of elements when said strip element is moved out of said path.

8. In combination with an apparatus for assembling Venetian blind slats, the provision of: a support and guide means for a slat comprising a stationary means supported adjacent to the path of said slat; a movable member carried by said stationary means and provided with oppositely disposed, pivotally mounted elements provided with upstanding flanges, said flanges being normally arranged in V-shape extending laterally into the path and with the apex of the V disposed in the direction of advancement of the slat; crank means carried by each element for engagement with said stationary means to position said flanges in parallel relation; and spring means to retract said pair of elements when said slat is moved out of engagement therewith.

9. A support and guide means for guiding an elongated slat along a path and to hold open an opening defined by spaced flexible tapes and transversely extending ladder elements while a slat is advanced into said opening, comprising in combination: a support means positioned adjacent to the path of said slat; a movable member carried by the support means and movable longitudinally of said path relative to the support means; a pair of pivotally mounted flanged elements normally extending partially across said path and carried by said movable member to extend into an opening; and means

13

carried by the support means for retracting said pair of elements.

10. In an apparatus for automatically assembling Venetian blind slats, the combination of: a frame structure; horizontally extending support and guide means on said frame structure for receiving a slat in a horizontal position; means to advance a slat onto said support and guide means; a member extending parallel to the path of said slat in spaced relation thereto and rotatable about its longitudinal axis; a first switch means carried by the frame structure and provided with a switch contact arm normally disposed in the path of an advancing slat, said first switch means being pivotally mounted on the frame structure; means connected to said first switch means and engaging said rotatable member whereby said switch contact arm is moved out of the path of a slat when said slat contacts said arm; said first switch means being adapted to cause rotation of said rotatable member; a
